INVENTOR,

Paul King.
by E. W. Anderson,
Attorney,

UNITED STATES PATENT OFFICE.

PAUL KING, OF WASHINGTON, DISTRICT OF COLUMBIA.

HARNESS.

SPECIFICATION forming part of Letters Patent No. 399,051, dated March 5, 1889.

Application filed August 25, 1888. Serial No. 283,708. (No model.)

To all whom it may concern:

Be it known that I, PAUL KING, a citizen of the United States, and a resident of Washington, in the District of Columbia, have invented certain new and useful Improvements in Harness; and I do declare the following to be a full, clear, and exact description of the invention, such as will enable others skilled in the art to which it appertains to make and use the same, reference being had to the accompanying drawing, and to letters or figures of reference marked thereon, which form a part of this specification.

The drawing is a representation of a portion of a harness showing my invention.

The invention relates to improvements in harness for animals; and it consists in the novel construction of the straps forming the harness.

It is well known that leather from which the hair has been removed by the process of tanning absorbs moisture through the openings left by the hair removed, so that the oils introduced by the tanner are soon expelled or neutralized by the moisture, rendering the leather hard and unpliant, and also that the pores become filled with dust, so that in subsequent oiling the oil will not penetrate equally throughout the leather. To obviate this difficulty I construct a harness of animal hide tanned with the natural hair remaining thereon.

All the straps of the harness, usually con-

structed of leather, are in my improved harness constructed of two layers of the tanned hide having their flesh sides in contact and stitched together, so that the hair is presented as a lining and also as a covering, as shown in the drawing, in which I have deemed it necessary to illustrate only a portion of the harness.

It will be obvious that the hair on the inner side not only presents a soft padded-like surface to the skin of a horse, but it also repels perspiration and prevents it from entering the leather, and on the same principle the hair on the outer side excludes or sheds rain and moisture.

The saddle and collar of the harness may be padded in the usual manner.

I am aware that it is not new to line portions of a harness with animal skin having the hair on; but in that event the outer surface is unprotected and made of ordinary leather.

Having described my invention, what I claim is—

A harness the straps of which consist of two layers of animal hide tanned with the hair on, said layers stitched together at their edges with their flesh sides in contact, substantially as specified.

In testimony whereof I affix my signature in presence of two witnesses.

PAUL KING.
